Fig. 1.

A technical line drawing of a mechanical assembly, possibly a pump or valve mechanism. The drawing shows a central vertical rod (4) with a handle (21) at the top. A horizontal tube (11) is attached to the rod. On the left side, there is a complex assembly with a gauge (6), a valve (12), and a gear-like component (10). Various other parts are labeled with numbers: 1, 2, 3, 5, 7, 8, 9, 13, 14, 15, 16, 17, 18, 19, 20, 22, 23, 24, 25, and 26. The drawing uses fine lines and cross-hatching to indicate different materials and assembly details.

UNITED STATES PATENT OFFICE

ALMON J. VAN DRESSER, OF NEW ORLEANS, LOUISIANA

TRACK-OILING DEVICE

Application filed December 8, 1927. Serial No. 238,661.

This invention relates to means for applying oil or other lubricant to track rails, and more particularly to the grooved guard rails commonly employed on curves in street rail-
5 way systems.

As is well known, guard rails of the character referred to, have, in addition to the usual tread, a flanged or guard portion usually projecting above the plane of the tread, 10 and separated therefrom by means of a groove which receives the flange of the wheels. In rounding curves considerable binding and friction develops between the wheel flange and the inner face of the flange of the guard rail, and it is customary to apply lubricant to this guard rail to facilitate the movement of the wheels on the curve.

Heretofore this work has been done exclusively by hand, that is to say the lubricant 20 is carried in a bucket and applied to the rail by means of a paddle or the like. The labor cost of this service is relatively high and adds materially to the cost of maintenance of the system.

25 The object of the present invention is to provide a manually propelled oiling device which may be pushed along a track rail as fast as a man can walk, and which will rapidly and effectively apply lubricant to the flange 30 of the guard rail at the point where it is required.

With the above general object in view, and to provide an apparatus of this character having simple and efficient details of construction, the invention consists in the combination and arrangement of parts hereinafter described and claimed, and illustrated in the accompanying drawings in which:

40 Fig. 1 is a side elevation of my improved lubricating apparatus;

Fig. 2 is a plan view thereof;

Fig. 3 is a section on enlarged scale on the line 3—3 of Fig. 1, looking in the direction of the arrows;

Fig. 4 is a fragmentary inverted sectional plan view on the line 4—4 of Fig. 1;

Fig. 5 is a longitudinal section through the delivery nozzle or brush; and

50 Fig. 6 is a transverse section on an en-

larged scale through the combined air pipe and trunnion.

Referring to the drawings in detail, my improved apparatus is in the form of a truck or wheeled support, comprising a suitable base 1 to which are secured at the ends outwardly and downwardly inclined bearing brackets or pedestals, in the ends of which are journalled a pair of spaced tandem wheels 3 adapted to roll upon the track rail X.

In order to propel the apparatus along I provide a handle 4 secured to the base 1 and provided at its upper end with a cross bar 5.

Secured to the base 1 are a pair of upstanding spaced brackets 6 which pivotally support a lubricant container 8. This is shown as comprising a cylindrical tank having a removable air-tight cover 9. In order to provide trunnions on which this tank is supported I secure in the upper part of the tank a horizontal, transversely extending pipe 7. One end of this pipe 7 is closed, as indicated at 7^b, while the other end is attached to a tube 10 connected with an air pump 11 secured to the handle 4. A pressure gauge 12 is preferably connected with the pipe 7 and tube 10 to show the amount of air pressure contained in the tank.

The portions of the pipe immediately outside of the container 8 are journalled in the upper ends of the brackets 6 and constitute trunnions on which the container 8 may swing.

As shown in Figs. 3 and 6, the pipe 7, on the inside of the container 8 is provided with ports 7^a which preferably open upwardly, through which ports the air from the pump 11 flows into the container and is compressed in the space above the lubricant therein, thus maintaining such lubricant under pressure.

The bottom of the container 8 preferably slopes toward the center, as shown at 8^a in Fig. 3, and rigidly mounted in this bottom at its lowest point is the upper end of a downwardly extending discharge pipe 13. This pipe works freely through a transverse slot 14 in the base 1, as clearly shown in Figs. 3 and 4, such slot permitting the pipe to swing laterally, as the container rocks on its trunnions. To the lower end of this discharge

pipe 13 is secured a delivery nozzle or brush 15. This preferably consists of a block 15^a secured to the laterally bent lower end of the discharge pipe 13 and having a central port through which the lubricant is delivered. In the pipe 13 between the container 8 and nozzle 15 is inserted a valve 16 by means of which the flow of lubricant through the pipe and nozzle may be controlled. This valve is provided with an operating lever 17 which is normally urged by a spring 18 into a position to close the valve 16. In order to open this valve as desired, an operating wire 19 is secured to the lever 17 and passes up through the handle 4, which is preferably hollow, to the upper end of such handle where it is secured to an operating lever 20, pivotally mounted at 21 on the cross bar 5.

Another wire 22 also passes up through the handle 4 and is secured at its lower end to a bell crank lever 23 pivoted at 24 to the lower side of the base 1 and connected through a spring 25 with the pipe 13. The upper end of the wire 22 is secured to an operating lever 26 pivoted at 27 to the cross bar 5. From the foregoing it will be seen that when the operating lever 20 is depressed the valve 16 will be opened and lubricant will be discharged under pressure from the container through the delivery nozzle. It will also be observed that when the operating lever 26 is depressed the bell crank 23 will be actuated and the discharge pipe 13, together with the container 8, will be swung laterally about the trunnions 7 in such a manner as to bring the delivery nozzle or brush 15 into engagement with the inner surface of the flange of the guard rail, as clearly shown in Fig. 3. By virtue of the spring connection 25 the brush or nozzle is yieldingly urged into contact with the surface of the rail, as described.

Referring again to Fig. 3, I have illustrated therein a guard rail X having the tread portion *x*, the flange *z* and the intermediate groove portion *y*, and it will be seen that the flange *z* is considerably above the tread *x*.

The wheels 3 of my improved truck are made to conform as closely as possible with the contour or profile of this rail, and to this end the periphery of each wheel is made up of a tread portion *a* adapted to roll upon the tread *x* of the rail, a smaller tread portion *c* adapted to roll upon the upper edge of the flange *z* of the rail, and a central rib *b* shaped to enter the groove *y* of the rail. It will thus be seen that the wheel comprises a central rib or bead with a tread portion at each side thereof, and that these tread portions bear upon the corresponding parts of the rail in such manner as to cause the wheels to be firmly supported. By providing wheels of this character I have produced a tandem truck which is capable of standing alone upon the track rail when released by the operator, and this is a feature of considerable practical importance.

By providing independent operating means for the valve 16, and for swinging the nozzle against the surface of the rail, I am enabled to control these two elements separately and may thus regulate each as desired.

By locating the delivery nozzle 15 at a point between the two wheels 3, the rear wheel serves to spread or distribute over the rail surface the lubricant which has been applied by the nozzle or brush 15. This is a matter of importance, especially in hot weather, since, if the oil or grease is not promptly spread or distributed, it will melt and flow away without perhaps reaching the entire surface which it is desired to have it cover.

In order to assist in lifting the apparatus from the track, and in carrying it about, I provide a bail 28 pivotally connected at 29 with the forward bearing brackets 2 and equipped with a handle 30.

From the foregoing it will be seen that I have provided a simple, convenient and compact apparatus by means of which lubricant under pressure may be rapidly and effectively delivered and applied to the flanges of guard rails, and it is thought that the many advantages of my invention will be readily appreciated without further discussion.

What I claim is:—

1. Rail lubricating apparatus comprising a truck wholly supported on two spaced tandem wheels movable along a rail, a lubricant container carried by said truck, and a discharge pipe extending downwardly from said container and disposed to deliver lubricant onto the rail, each of said wheels having a central peripheral rib and an annular flange or tread on each side thereof, whereby said truck will stand alone on a grooved track rail in upright position.

2. Apparatus for lubricating track rails having a head, groove and guard flange, said apparatus comprising a lubricant container and a truck on which said container is mounted, said truck having a pair of spaced tandem wheels on which it is wholly supported, and each of said wheels having a periphery corresponding in transverse profile to the transverse profile of the rail, such periphery comprising an annular rib adapted to fit into the groove of said rail.

3. Rail lubricating apparatus comprising a wheeled support movable along a rail, a lubricant container, horizontal trunnions on which said container is mounted to swing, relative to said support, one of said trunnions being hollow, an air pump connected with said hollow trunnion for compressing air in said container, a discharge pipe rigid with said container and swinging therewith, and means for swinging said container on its trunnions.

In testimony whereof I affix my signature.

ALMON J. VAN DRESSER.
